CLAIM

The ornamental design for a wireless earbud, a shown and described.

DESCRIPTION

This application is related to application Ser. No. 29/709, 192, entitled Wireless Earbuds and Charging Case Assembly, filed on Oct. 11, 2019, the disclosure of which is incorporated herein by reference.

FIG. 1 is a front perspective view of the wireless earbud according to a first embodiment of our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front perspective view of the wireless earbud according to a second embodiment of our new design;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top plan view thereof; and,

FIG. 14 is a bottom plan view thereof.

The broken lines shown in the drawings illustrate portions of the wireless earbud that form no part of the claimed design.

The dot-dash lines in FIGS. 1, 3-4, and 6-7 are boundary lines that form no part of the claimed design.

1 Claim, 14 Drawing Sheets
